STAMPER PRESS WITH GRIPPING FINGERS

Vincent E. Cottrell and Simon Deringer, Philadelphia, Pa., assignors to Easy Way Stamper Machine Company, Inc., Philadelphia, Pa., a corporation of Pennsylvania

Application May 2, 1955, Serial No. 505,220

6 Claims. (Cl. 223—12)

This invention relates to a labor saving attachment 15 for a conventional or pneumatically operated stamper press or hat blocking machine and is an improvement over the device disclosed in our co-pending application Serial No. 455,230, filed September 10, 1954. The present application is a continuation-in-part of our co-pending application hereinabove specified.

The primary object of this invention is to provide an attachment to a stamper press having fingers operable to grip one edge of hat material which is draped over the stationary mold prior and up to the time that the complementary movable mold is moved into engagement with the material. This entirely eliminates the need for one of the two operators presently used to hold the hat material in a stretched condition in the conventional stamper presses.

Another important object of the invention is to provide a material-gripping attachment for a stamper press which can be actuated to selectively grip and release the material independently of the means required to move the shaping molds into engagement with each other.

A further important object of this invention is to provide a material-gripping attachment of the character described which is equipped with easily operable means to move and adjust the gripping members vertically, 40 horizontally and towards and away from each other to accommodate hat material draped over molds of a wide variety of sizes and shapes.

Another object of the invention is to provide a material-gripping attachment of the character described 45 which is effective for use on modern multi-ply hat materials.

Another object of the invention is to provide a device of the character described which can be simply, efficiently, and effectively operated by a valved pneumatic actuating means.

Yet another object of the invention is to provide a material-gripping attachment of the character described which can be readily and easily assembled upon a stamper press and can be readily and easily removed therefrom for replacement and repair of parts.

And yet another object of the invention is to provide a material-gripping attachment which can be installed upon a bank of stamper presses which can be readily and easily operated in a timed sequence by a single operator, thus effecting important savings in time and labor.

These and other objects of the invention will become more apparent as the following description proceeds in conjunction with the accompanying drawings, wherein:

Figure 1 is a perspective view of the device shown attached to a pneumatically operated stamper press;

Figure 2 is a fragmentary enlarged side elevational view of the device with parts broken away to show details of construction;

Figure 3 is a view looking from the plane and in the direction of the arrows of the line 3—3 of Figure 2;

2

Figure 4 is a sectional view taken on the line 4—4 of Figure 2;

Figure 5 is a sectional view taken on the line 5—5 of Figure 3;

Figure 6 is a sectional view taken on the line 6—6 of Figure 3;

Figure 7 is a sectional view taken on the line 7—7 of Figure 4;

Figure 8 is an enlarged elevational view of one of the gripping members shown in the open position with parts broken away to illustrate details of construction;

Figure 9 is a diagrammatic view illustrating the placement of the hat material on the mold and the gripping member in position to engage one edge of the material; and

Figure 10 is a view similar to Figure 9 and illustrating the manner in which the gripping member engages the hat material.

Specific reference is now made to the drawings where 20 in similar reference characters are used for corresponding elements throughout.

While the drawings illustrate the present device in association with a pneumatically operated stamper press as disclosed in our co-pending application Serial No. 411,165, it will be understood that the device can be used on any stamper press which employs a female mold movable to engage material draped over a male mold. The most efficient use of the device is in association with a pneumatically operated stamper press.

The stamper press is generally indicated at 10 and the present material-gripping attachment at 12. The press comprises any suitable support 14, preferably in the form of a table to the top of which is removably secured as at 16 a male mold 18 of desired size and contour and over which the hat material 20 is adapted to be draped. A complementary female mold 22 is supported above the male mold and is movable into and out of engagement with the hat material 20 on the stationary mold 18. Both molds are equipped with conventional heating means required in the molding of the hat material.

While mechanical means may be used to raise and lower the mold 22, pneumatic means is more efficient. In the latter case, a pair of uprights 24 are secured on the support 14 upon which is slidably mounted a cross bar 26, the latter being equipped with terminal collars 28 and set screws 30 to adjust the position of the cross bar. Mounted on the cross bar is a cylinder 32 in which a piston rod (not shown) is slidable, the latter being operatively connected to the movable mold 22. The upper and lower portions of the cylinder 32 are communicated to conduits 34 and 36 that are in turn operatively connected to a trippable (preferably foot operated) 4-way treadle valve 38, the latter being connected to an air compressor 40 by means of a suitable conduit 42. Movement of the treadle valve 38 in one position or in another will selectively admit air under pressure to the top of the cylinder 32 through the conduit 34, or exhaust air from the bottom of the cylinder through the conduit 36, thereby lowering and raising the mold 22. As will appear hereinafter, the movement of the mold 22 is independent and separate from the operation of the gripping members of the present device 12.

Coming to the device 12 itself, the same comprises a transverse rod or tube 44 carrying substantially F-shaped clamps 46, the arms of which engage the rear edge of the table or support 14 there to be secured by appropriate clamping screws 48, as will be evident more particularly from Figures 2, 4 and 7.

Mounted on the ends of the tube 44 is a pair of upright rods 50 and 52. Slidable on the rods are tubes 54

and 56 to which are welded or otherwise secured a preferably channel shaped U-frame 58 including a cross member 60. A vertically extending screw 62 is provided having an appropriate handle 64 at its lower end, the screw being rotatably journaled through appropriate threads centrally in the member 44 and being further appropriately secured at its upper end as at 66 to the cross member 60 of the frame 58. Thus the turning of the screw 62 will adjustably raise and lower the tubes 54 and 56 and the frame 58 associated therewith.

Extending rearwardly of the tubes 54 and 56 are bars 68 and 70 having open angulated slots 72 and 74 which receive threaded pins 76 and 78. The pins extend from the sides 80 and 82 of a second frame 84 and are retained on the tubes 54 and 56 by appropriate nuts 86 and stop bars 88. The frame 84 is generally U-shaped and preferably channel in cross section and therefore includes a rear transverse member 90 interconnecting the side members 80 and 82.

A third frame 92 is provided which is substantially rectangular. The frame 92 includes a bottom transverse member 94, a top transverse member 96 to which a reflecting surface or mirror 98 is secured at an angle and generally vertically extending side members 100 and 102. The side members 100 and 102 adjacent the bottom member 94 are provided with transverse extensions 104 and 106 which slidably engage in the channel side members 80 and 82 of the second frame 84. An elongated screw 108 having a handle 110 at its end is rotatably journaled in a threaded bearing 112 which is carried by the rear transverse member 90 of the second frame 84. At the end opposite the handle, the screw is secured by any appropriate means as at 114 to the lower transverse member 94 of the third frame 92. Thus the rotation of the screw 108 will adjustably move the third frame 92 as a unit towards and away from the stationary mold 18.

It is the third frame 92 which mounts the material-gripping members. Secured intermediate the ends of the side members 100 and 102 and extending transversely of the frame 92 is a bar 116 which serves to mount the gripping members generally indicated at 118, the details of which are shown more particularly in Figure 8. Two gripping members are preferred and each consists of elongated fingers 120 and 122 which are pivoted intermediate their ends as at 124. The forward end of the upper finger 120 is in the form of a toothed gripping jaw 126 and the forward end of the lower finger 122 is provided with a sponge rubber anti-friction member 128. A spring 130 is terminally secured to the inner faces of the upper and lower fingers 120 and 122 and is tensioned to normally urge the forward or jaw portions of the fingers in an open position as shown particularly in Figures 3 and 8.

The transverse bar 116 includes a pair of elongated slots 132 and 134 and the rear portion of the lower finger 122 includes a groove 136 which slidably receives the bar 116. The rear portion of the lower finger 122 also carries a pin 138 which extends loosely through the slot 132 or the slot 134, the pin 138 including a head 140 and spaced washers 142 between which is retained a spring 144 serving to urge the lower finger 122 into engagement with the bar 116. The spring 144 also serves as a shock absorber when the jaws are urged into a material-gripping or closed position. The position of the gripping members 118 towards and away from each other can be adjusted by means of a set screw 146 which extends through the rear portion of the lower finger 122 and which is adapted to bear against the rear portion of the bar 116 at a predetermined location.

The selective closing and opening of the gripping members 118 is effected by a means which is operable independently of the means to raise and lower the movable complementary mold 22. This means includes a transverse rod 148 which extends between the rear portions of the fingers 120 and 122. This rod is slidably engaged at its ends in channels 150 and 152 which are carried by the

vertically extending side members 100 and 102 of the third frame 92. Radially secured to the rod 148 is a piston rod 154 which extends slidably into a cylinder 156 which is carried by the upper member 96 of the third frame 92. The cylinder 156 is communicated with a conduit 158 which is operatively connected to the air compressor 40 by means of a conventional 3-way tripable (preferably foot operated) treadle valve 160. The connection of the treadle valve 160 to the compressor 40 may be effected by a conduit 162 which may also be connected to the conduit 42 by an appropriate T fitting 164. Thus both the treadle valve 38 and the treadle valve 160 may be communicated to the same compressor 40 but are separately and independently operable. When the treadle valve 160 is moved to one position, air under pressure will enter the conduit 158 and raise the piston rod 154 which will, in turn, raise the rod 148 and urge the gripping fingers into the closed position as shown in Figure 10. When the treadle valve 160 is moved to the opposite position, the compressed air is withdrawn from the conduit 158 so that when the springs 130 urge the gripping fingers into the open position, the rod 148 is pulled down as shown in Figure 9.

In use, the screws 62 and 108 are actuated so that the frame carrying the gripping members assumes the desired adjusted position relative to the stationary mold 18. The set screws 146 are loosened and then retightened when the gripping members 118 have been adjusted relative to each other to the position necessary to grip one edge of the hat material 20. All of these adjustments are required to accommodate the gripping members to a wide variety of sizes and shapes of molds. An operator places the hat material 20 over the mold 18 so that the rear edge thereof extends into the open jaws of the gripping members as shown in Figure 9. The treadle valve 160 is then actuated so that the jaws close upon the hat material as shown in Figure 10 and the operator then applies tension to the hat material to stretch it on the mold 18. The treadle valve 38 is then operated so that the upper complementary female mold 22 is lowered into engagement with the hat material 20. At the point of engagement, the treadle valve 160 is again operated so that the gripping members are forced open to release the hat material. This is required to permit the hat material to slip into the proper contour of the molds. This is particularly necessary when operating with modern multi-ply hat material which usually contains three thicknesses of material including a lining, buckram, and any other desired material.

This material requires wetting and a certain predetermined drying time in the molds before a fixed shape is imparted to it. It is not possible to obtain proper contouring of these multi-ply hat materials if the gripping fingers are compelled to engage and hold the hat material for the entire time that the molds 18 and 20 are closed because this prevents the required slippage of the hat material into the mold as mentioned hereinabove.

The gripping members described herein may be attached to a battery or series of machines for operation by a single operator in a timed sequence. The final operation is to actuate the treadle valve 38 again whereby the upper mold 22 is moved out of engagement with the lower mold 18 to permit removal of the contoured hat material from the stamper press.

While a preferred embodiment of the invention has been shown and described hereinabove, skilled artisans may make minor variations without departing from the spirit of the invention and the scope of the appended claims.

We claim:

1. In a stamper press including a support, a stationary mold mounted thereon, a complementary mold mounted on said support over said stationary mold, means to lower and raise said complementary mold into and out of engagement with said stationary mold; fingers adapted to

grip one edge of material to be draped over said stationary mold, means to open and close said fingers operable independently of said complementary mold lowering and raising means, a frame mounted on said support, means to adjustably raise and lower said frame, means mounting said fingers on said frame for adjustable positioning towards and away from each other, and means to adjustably move said fingers in unison towards and away from said stationary mold.

2. The combination of claim 1 wherein said support includes upstanding rods, said frame includes a cross-member and terminal tubes slidably embracing said rods and said means to adjustably raise and lower said frame includes a turn-screw journaled in said support and secured to said cross-member.

3. The combination of claim 1 wherein each of said fingers includes spring-urged pivotally interconnected jaw members, said frame includes a bar, and said means mounting said fingers on said frame for adjustable positioning towards and away from each other includes spaced longitudinal slots in said bar, a groove in one of said jaw members slidably receiving said bar, a pin depending from said one of said jaw members and extending through one of said slots, spring means associated with said pin and acting to urge said one of said jaw members against said bar, and a set screw carried by said one of said jaw members and adapted to bear against said bar.

4. The combination of claim 1 wherein said frame includes a pair of side members interconnected by a cross-member and said means to adjustably move said fingers in unison towards and away from said stationary mold includes a bar carrying said fingers and slidably engaged at

its ends in said side members, and a turn-screw journaled in said cross-member and secured at one of its ends to said bar.

5. In a stamper press including a support, a stationary mold mounted thereon, and a complementary mold mounted over said stationary mold for movement into and out of engagement therewith; fingers adapted to grip one edge of material to be draped over said stationary mold, means to open and close said fingers independently of the movement of said complementary mold, a frame carrying said fingers and mounted on said support, means operative on said frame to adjustably move the same vertically on said support, and means to adjustably move said fingers towards and away from each other.

6. In a stamper press including a support, a stationary mold mounted thereon, and a complementary mold mounted over said stationary mold for movement into and out of engagement therewith; fingers adapted to grip one edge of material to be draped over said stationary mold, means to open and close said fingers independently of the movement of said complementary mold, a frame carrying said fingers and mounted on said support, means to adjustably move said fingers towards and away from each other and means operative on said fingers to adjustably move them in unison towards and away from said stationary mold.
